DEVICE FOR SPREADING ROAD MATERIAL

John Eric Chadwick, Toronto, Ontario, Canada

Application September 11, 1933, Serial No. 688,933

4 Claims. (Cl. 275—8)

This invention relates to a device for spreading road material.

The device has been designed to spread chips, in the process of road making, but it is possible 5 that it may be readily applicable to the spreading of gravel, sand and other like materials.

The objects of the invention, generally, are to improve on known spreading devices.

A specific object of the invention is to provide 10 a spreader unit which can be easily attached to the rear of a dump truck so as to gradually receive the load as it is being discharged from the truck body and to spread the same gradually.

Another specific object is to provide a self-operated spreader unit, that is, one having its own power plant and operating irrespective of the travel or speed of the truck from which it is suspended.

Another specific object is to provide means for adjusting the position of the spreader unit to preferably a same horizontal position, irrespective of the position of the dump body.

Another specific object is to regulate the range 25 or spread of the material as well as its rate of discharge.

In the drawings, wherein like numerals of reference indicate corresponding parts in the various figures;

Figure 1 is a fragmentary side elevation of a typical dump truck with my device in operative position.

Figure 2 is a similar view to Figure 1 but showing the dump body tilted as in process of discharging the load.

Figure 3 is a rear elevation of the device unit.

Figure 4 is a front elevation of Figure 3, with the forward wall partly broken away.

Figure 5 is a diagrammatic view of the door 40 shifting mechanism.

Figure 6 is a fragmentary, enlarged side elevation of the rear hook or support for the spreader unit or device.

Figure 7 is a fragmentary, enlarged centre 45 cross section through the hopper.

Figure 8 is a fragmentary, enlarged view of the hopper showing the hopper locking means.

Figure 9 is a section through the top portion 50 of the tail gate showing the hook in position.

Figure 10 is an enlarged section through the hopper showing the winch device in position.

Figure 11 is a fragmentary, enlarged plan view of the hopper door.

Figure 12 is a side elevation of Figure 11.

Referring now by numerals to the drawings,

10 indicates in part only, a typical dump truck of which 11 is the dump body. The body is hinged to the chassis 12 as at 12A and has the usual tail gate or rear door 14 hinged at the top. In the type of truck shown, there are provided I-beams 13 arranged longitudinally under the dump body and forming part of the underframe thereof, these beams extending to the rear of the underframe.

The device, as shown, is designed to fasten or 10 hook onto the dump body illustrated, or more particularly to hooks 17 from the I-beams, but it is evident that the device is equally capable of being hooked onto other similar dump bodies by merely changing, if necessary, the position 15 or shape of the hooks.

Briefly stated, the device comprises a hopper adapted to be hooked to the rear of the dump body of a truck, the open top of the hopper receiving the load being discharged from the 20 dump body and the bottom being closed or opened by means of sliding gates; of means for opening or closing the open bottom of the hopper; of a rotary distributor or spreader element mounted under the hopper and in a position to receive the material dropping out of the 25 hopper; of a unit power plant carried by the hopper for actuating the distributor; and of a winch and cable device for adjusting the position of the hopper with respect to the dump body 30 with a view to holding the hopper in a same horizontal position when spreading the material upon the road.

The hopper is shown at 14A and is formed with slightly slanted forward and rearward walls 35 15 and 16, respectively, and slanted walls 18 and 19. The forward wall 15 is provided with two spaced apertures 20, and preferably a longitudinal bar 21 adjacent the apertures. From the I-beams of the truck body extend the 40 two bars 17 formed with notches 17A, the hooks so formed being received into the apertures 20 with the notches engaging the upper edges of said apertures, so that the hopper may be suspended at the rear from the bars or hooks 17. 45 To releasably lock the hopper in its suspended position from the hooks 17, as aforesaid, locking pins 22 may be inserted into an aperture 23 made through the hook in a position to lie within the hopper when the same is suspended 50 from the hooks.

In order to support the rear end 16 of the hopper as well as to raise or lower the same as desired, there is provided the winch and cable device 24 aforesaid. On the free end of the 55

cable 25 is a hook 26 formed and adapted to hook onto the top of the tail gate, the other end of the cable being anchored to and wound around the shaft or spindle of the winch device. The winch device is preferably secured to the hopper at mid length. For the purpose of so securing the winch, an angle member 28 may be used, one leg of which is bolted to the rear wall of the hopper and the upper leg of which receives the winch proper. Thus, it will be seen that by operating the winch to lengthen or shorten the cable, the rear end of the hopper will be accordingly lowered or raised, respectively, to maintain the hopper in a vertical or proper discharging or spreading position irrespective of the dumping position of the truck body.

The hopper gates aforesaid, are preferably made in two sections 29 and 29A, these sections 20 sliding on tracks or angles 30 mounted to extend below the open bottom of the hopper. To slide the gate sections toward or away from one another to accordingly close or open the hopper bottom, suitable means are provided 25 which preferably are operable by a lever 31 mounted on the rear wall of the hopper. As shown, this lever is fixed to the rear end of a shaft 32 journalled in brackets 33 from the hopper, the shaft extending beyond the forward wall 15. Fixed to this shaft, preferably at mid 30 length thereof, is a crank 34, the lower end of which is operatively connected to the gate section 29A by means of a link 35 pivotally connected between said crank and a pair of lugs 36 from the gate section. Thus, by turning the lever 31 in a clockwise direction, the gate section 29A is shifted toward the centre of the hopper. By turning the lever in the opposite direction, on the other hand, the gate section 40 is shifted away from the centre of the hopper. On the end of the hopper adjacent the gate section 29 is a shaft 32A journalled in brackets 33A from the hopper; fixed to the shaft 32A, preferably at mid length thereof, is a crank 34A operatively connected to the gate section 29 by means of a link 35A pivotally connected between the lower end of the lever and lugs 36 from the gate section. Fixed to the front 45 ends of the shafts 32 and 32A are cranks 37 and 37A respectively, the free ends of which are directed in opposite directions from their respective shafts and are operatively connected together by means of a link 38 pivotally connected therebetween. Thus, by turning or operating 50 the lever 31, the two gate sections are moved simultaneously in opposite directions and to an equal extent.

To releasably lock the gate sections in different relative positions, a ratchet device may be used. 60 As shown, a quadrant 40 is secured to the rear wall of the hopper adjacent the handle or lever 31; mounted on the lever is a spring-pressed bolt or latch 41 co-operating with the quadrant.

In order to handle or lift the device complete, as in process of applying the same to or removing it from the dump body, handles 42 are provided at each end of the hopper, these preferably being braced as with pipe sections 43.

From the hopper, and forming an integral 70 part of the device, is a platform 44 upon which the operator may stand.

Mounted below the bottom of the hopper is a spreader 46 adapted to receive chips being discharged from the hopper and to scatter or throw the same radially from the spreader upon

the road. This spreader has a circular plate or disc 47 formed with radially arranged vanes 48 which serve to throw the chips outwardly from the centre of the disc. From the hub 49 of the disc is a shaft 50 journalled in a housing 51 suitably secured in the vertical axis of the hopper as with brackets 52 and 53. Fixed adjacent the upper end of the shaft 50 is a bevel gear 54 meshing with a second bevel gear 55 fixed on a shaft 56 journalled in the transmission housing. On the outer or rear end of the shaft 56 and positioned to lie outside of the hopper is fixed a pulley 57. Thus, the spreader 46 may be revolved by the rotation of the pulley 57.

To actuate the spreader, a unit power plant is provided, this taking the form of a suitable low powered gasoline engine A, mounted on the platform. Between the engine pulley 58 and the pulley 57 is loosely trained a belt 60. An idler 61, journalled in a bracket 62 pivotally connected to the hopper as at 63, is normally held against one side of the belt, to tighten the same, by means of a spring 64. To release the belt and to allow the engine pulley to run free from any load, the idler is spaced from the belt by means of a foot pedal 66 from the bracket 62. Thus, the spreader may be actuated and idled alternatively, by the operator who releases or presses upon the pedal.

Operation

Once in position, hanging from the rear of the dump body or more particularly from the hooks 17, with the hook 26 of the winch device 35 in position on the tail gate 14 and the hopper substantially horizontal, the tail gate is unlocked, and the dump body slowly raised or hoisted. While the dump body is being raised, the operator now standing on the platform proceeds to 40 operate the winch device to gradually raise the rear end of the hopper so as to maintain the same in a horizontal or proper spreading position. The material in the dump body gradually discharges into the hopper until the hopper is 45 fairly well filled. The truck is next propelled, the engine started to revolve the spreader and the sliding gates opened to the required extent. As the material falls out of the hopper onto the 50 spreader, it is thrown outwardly onto the road. In so suspending the spreader above the road and below the hopper bottom, as well as some distance away from the rear wheels of the truck, the material is spread evenly in all directions.

What I claim is:—

1. For use in combination with a dump truck having a tail gate swingable rearwardly from the bottom and supports extending rearwardly from the dump body of said truck, a removable material spreader unit comprising a hopper adapted to rest at the forward end upon said supports whereby the rearward end of said hopper is free to swing from the bottom, said hopper being formed to allow said gate to swing thereover to discharge material thereinto when said dump body is tilted and terminating in an opening for the discharge of the material, a rotor positioned to receive the material falling out of said hopper, a door under said opening operable to vary the rate of discharge of the material, means for actuating said rotor, and adjustable means from the rearward end of said hopper adapted to removably engage said truck body above said supports and operable to move said rearward end relatively to said body where- 75

by said rotor may rotate in a horizontal plane irrespective of the tilted position of said body.

2. For use in combination with a dump truck having a tail gate swingable rearwardly from the bottom and supports extending rearwardly from the dump body of said truck, a removable material spreader unit comprising a hopper adapted to rest at the forward end upon said supports whereby the rearward end of said hopper is free to swing from the bottom, said hopper being formed to allow said gate to swing thereover to discharge material thereinto when said dump body is tilted and terminating in an opening for the discharge of the material, a rotor positioned to receive the material falling out of said hopper, a door under said opening operable to vary the rate of discharge of the material, means for actuating said rotor, and adjustable means from the rearward end of said hopper adapted to removably engage the top of said tail gate above said supports and operable to move said rearward end relatively to said body whereby said rotor may rotate in a horizontal plane irrespective of the tilted position of said body.

3. For use in combination with a dump truck having a tail gate swingable rearwardly from the bottom and supporting means adjacent the rearward end of the dump body thereof, a removable material spreader unit comprising a hopper adapted to be hingedly supported at the forward end to said supporting means whereby the rearward end of said hopper is free to swing from the bottom, said hopper being formed to allow said gate to swing thereover to discharge material thereinto when said dump body is tilted and terminating in an open-

ing for the discharge of the material, a rotor positioned to receive the material falling out of said hopper, a door under said opening operable to vary the rate of discharge of the material, means for actuating said rotor, and adjustable means from the rearward end of said hopper adapted to removably engage said truck body above said supporting means and operable to move said rearward end relatively to said body whereby said rotor may rotate in a horizontal plane irrespective of the tilted position of said body.

4. For use in combination with a dump truck having a tail gate swingable rearwardly from the bottom and supporting means adjacent the rearward end of the dump body thereof, a removable material spreader unit comprising a hopper adapted to be hingedly supported at the forward end to said supporting means whereby the rearward end of said hopper is free to swing from the bottom, said hopper being formed to allow said gate to swing thereover to discharge material thereinto when said dump body is tilted and terminating in an opening for the discharge of the material, a rotor positioned to receive the material falling out of said hopper, a door under said opening operable to vary the rate of discharge of the material, means for actuating said rotor, and adjustable means from the rearward end of said hopper adapted to removably engage the top of said tail gate above said supporting means and operable to move said rearward end relatively to said body whereby said rotor may rotate in a horizontal plane irrespective of the tilted position of said body.

JOHN ERIC CHADWICK.
